UNITED STATES PATENT OFFICE.

GEORGE CHARLES JOHNSON TOPP, OF RYDE, ISLE OF WIGHT, ENGLAND.

NAVAL OR MILITARY ARTILLERY.

SPECIFICATION forming part of Letters Patent No. 770,200, dated September 13, 1904.

Application filed December 28, 1903. Serial No. 186,902. (No model.)

To all whom it may concern:

Be it known that I, GEORGE CHARLES JOHNSON TOPP, a subject of the King of Great Britain, residing at Ryde, Isle of Wight, England, have invented certain new and useful Improvements in Naval or Military Artillery; and I do hereby declare the following to be a full, clear, and exact description of the invention, such as will enable others skilled in the art

10 to which it appertains to make and use the same.

This invention relates to naval and military artillery, the object of which is to increase the life of the long and costly guns of the present day. I propose to use stays of sufficient strength to counteract the tendency to deflection due to concussion when the guns are fired. I will now describe the same in reference to the accompanying drawings, in which—

20 Figure 1 shows a heavy gun fitted with suitable heavy stays and lifting-gear. Fig. 2 shows a lighter gun with saddle moved forward on the gun. Fig. 3 shows a light gun also with another variation of applying the 25 position of stays. Fig. 4 shows front view of gun with stays lying in position, drawn to a larger scale. Fig. 5 shows back or breech of gun with stays carried right round underneath, also to a larger scale.

30 These stays are fitted to the guns in such a way that they run from under side of the breech A, Figs. 1 and 2, over a bridge B, designed to be raised by screw or other power, and then down to under side of chase C, Figs. 35 1, 2, 3, 4, and 5, where they are secured by any convenient and suitable means, as by fitting in a tongued groove formed in the gun-barrel at points A and C, the same being hidden in the views by the thickness of the stays.

40 When the bridge B is raised, a powerful lifting-support is brought to bear on the chase C, so that the tendency to droop or bend is overcome, and the gun's life is thereby greatly prolonged. The bridge is made in two parts.

45 (Shown at Figs. 4 and 5.) The lower part E is a saddle that sits on the gun-barrel. This saddle is fitted with very powerful screw-bolts D D, or these, if desired, can be fitted to the crown of the bridge, on which bolts and 50 nuts G G operate to raise the crown of the

bridge B. (Shown at Figs. 1, 2, 3, 4, and 5.) The stays run from under breech A over the bridge B to under chase C. When the bridge is raised to its extreme point of tension, I fit wedges F F, Figs. 4 and 5, or other suitable means under the crown B, and when these wedges or other means are driven home the weight is taken off the lifting parts of the gear.

55 S S, Figs. 4 and 5, show apex of stays resting on the bridge B.

With proper attention by the help of this invention the guns may be kept in a true line of bore and serviceable even until the bore is worn out by scoring of shot or otherwise. 65 Of course if the gun-bore gets out of true, as is the case sooner or later with present very long guns, its life for service is ended; but this method braces and supports the weak part in such a way that the gun can be kept in good 70 working order for a much longer time than at present, and the cost of working is much reduced.

This invention enables the gunner to assist the weak part of the gun (the chase) and it is 75 desirable that after each day's firing the lifting power should be adjusted, as all metals will stretch under great strains, and thus the stays will meet any inclination there may be for deflection of chase.

80 By the aid of this invention, with sufficient strength of stays and lifting power, a gun may be kept in true line for a much longer time under fire than without such assistance.

In new guns the stays should be fitted before use, as thereby they may be very greatly saved. Even after the gun is used up by the bore scoring or becoming unserviceable the stays and lifting-gear may be fitted on another similar gun, as they may outlive, perhaps, two guns' active service.

Having now described and ascertained the nature of my said invention and in what manner the same is to be performed, I declare that what I claim is—

1. The combination in ordnance of the character described, of the gun-body, and means to prevent sagging of the gun-muzzle comprising a bridge mounted on the gun-body, a stay passing over said bridge and secured to 100

the breech and chase of the gun, means for adjusting the height of said bridge and means independent of said adjusting means for taking the strain therefrom when in final position, substantially as described.

5. The combination in ordnance of the character described, of the gun-body and means to prevent sagging of the gun-muzzle comprising an endless flexible stay looped under the breech and chase of the gun, a bridge mounted on the gun-body under said stay, means for adjusting the height of said bridge and means independent of said adjusting means for taking the strain therefrom when in final position, substantially as described.

10. The combination in ordnance of the character described of the gun-body and means to prevent sagging of the gun-muzzle comprising a bridge mounted on the gun-body consisting of a saddle and a crown, means for adjusting said crown to any desired height, means independent of the adjusting means for supporting said crown when raised, and a stay passing over said crown and secured to the breech and chase of the gun, substantially as described.

15. The combination in ordnance of the character described of the gun-body and means to prevent sagging of the gun-muzzle comprising a bridge mounted on the gun-body consisting of a saddle and a crown, means for adjusting said crown to any desired height, lifting-bolts for adjusting said crown whereby said stay may be kept taut under all conditions and a wedge for independently supporting said crown when raised, substantially as described.

20. The combination in ordnance of the character described of the gun-body and means to prevent sagging of the gun-muzzle comprising a bridge mounted on the gun-body consisting of a saddle and a crown, lifting-bolts for adjusting said crown to any desired height, a wedge for independently supporting

25. said crown when raised and a stay passing over said crown and secured to the breech and chase of the gun, substantially as described.

5. The combination in ordnance of the character described of the gun-body, and means to prevent sagging of the gun-muzzle comprising a flexible stay looped under the breech 40 and chase of the gun, a bridge comprising a saddle and a crown mounted on said gun-body under said stay, means for adjusting the height of said crown, and means independent of said adjusting means for taking the strain 45 therefrom when in final position, substantially as described.

6. The combination in ordnance of the character described of a gun-body and means to prevent sagging of the gun-muzzle comprising an endless flexible stay looped under the breech and chase of the gun, a bridge consisting of a saddle and a crown mounted on said gun-body and under said stay, lifting-bolts for adjusting said crown whereby said stay may be kept taut under all conditions and a wedge for independently supporting said crown when raised, substantially as described.

50. In testimony whereof I affix my signature this 14th day of December, 1903, in presence of two witnesses.

GEORGE CHARLES JOHNSON TOPP.
